US00D824119S

(12) **United States Design Patent** (10) Patent No.: **US D824,119 S**
(45) Date of Patent: **** Jul. 24, 2018**

(54) **FEEDER**

(71) Applicant: **ZHUHAI HENGQIN SUPER TECHNOLOGY LTD.**, Zhuhai, Guangdong (CN)

(72) Inventors: **Tianle Yang**, Guangdong (CN); **Yibao Zeng**, Guangdong (CN)

(73) Assignee: **ZHUHAI HENGQIN SUPER TECHNOLOGY LTD.**, Zhuhai (CN)

(**) Term: **15 Years**

(21) Appl. No.: **29/610,702**

(22) Filed: **Jul. 14, 2017**

(30) **Foreign Application Priority Data**

Apr. 27, 2017 (CN) 2017 3 0148126

(51) LOC (11) Cl. **30-03**

Primary Examiner — Susan Moon Lee

(57) **CLAIM**

The ornamental design for a feeder, as shown and described.

DESCRIPTION

FIG. 1 is a front elevational view of a feeder showing our new design;

FIG. 2 is a rear elevational view thereof;

FIG. 3 is a bottom plan view thereof;

FIG. 4 is a left side view thereof;

FIG. 5 is a right side view thereof;

FIG. 6 is a first perspective view thereof;

FIG. 7 is a second perspective view thereof;

FIG. 8 is a third perspective view of the feeder showing the feeder bowls in a collapsed state; and,

FIG. 9 is a fourth perspective view showing the feeder in a rolled-up state.

1 Claim, 9 Drawing Sheets
